Inventor

W. M. Lanspa

UNITED STATES PATENT OFFICE

WILLIAM M. LANSPA, OF DAVID CITY, NEBRASKA

WINDMILL AND PUMP ROD COUPLING

Application filed May 6, 1931. Serial No. 535,545.

This invention relates to pumps, and more particularly to a coupling designed for use in coupling the usual windmill rod to the pump rod of a pump.

5 The primary object of the invention is the provision of means whereby the pump may be manually operated while the windmill rod is connected with the pump rod.

10 A further object of the invention is to provide a coupling including a pivoted section which may be disconnected from the pump rod and moved laterally out of the path of travel of the pump rod when the pump rod is operated by the usual pump jack.

15 With the foregoing and other objects in view, which will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

Referring to the drawings:

Figure 1 is an elevational view disclosing a coupling constructed in accordance with the invention, the sleeve or body portion of 30 the coupling being shown as swung laterally out of alignment with the pump rod.

Figure 2 is an elevational view showing the coupling as connected with the windmill rod and pump rod.

35 Figure 3 is a side elevational view thereof.

Figure 4 is an elevational view illustrating a coupling wherein the elongated opening or slot is formed in the sleeve.

Referring to the drawings in detail:

40 The reference character 5 designates a pump, which is of the usual and well known construction, the same having the usual pump rod 6, to which the windmill rod, pump jack or pump handle may be connected to operate the pump.

As clearly shown by the drawings, the pump rod 26 is formed with an elongated opening or slot 7, to accommodate the bolt 50 8 that is extended through openings formed

in the sleeve 9, constituting the body portion of the coupling.

The sleeve 9 is adjustably connected with the windmill rod 10, as by means of the securing plates 11, that are shown as engaging opposite sides of the windmill rod 10, where they are secured in close engagement therewith, by means of the bolts 12 and nuts 13, mounted thereon. The sleeve 9 has one edge thereof cut away throughout a portion of its length, so that the sleeve 9 may be swung laterally to a position as shown by Figure 1 of the drawings, should it be desired to operate the pump rod by means of a power jack 14.

55 Extending from the pump body is an arm 15 to which the pump handle 16 is pivotally connected, the handle being formed with an opening near its inner end, the opening being designed to receive a bolt used to connect the handle to the pump rod.

60 From the foregoing it will be obvious that should it be desired to operate the pump manually, while the windmill is connected therewith, it is obvious that by moving the handle to a position to bring the inner end thereof opposite to the opening of the pump rod that receives the bolt for connecting the handle to the pump rod, the bolt may be inserted and the pump rod 6 moved by the pump handle, the slot 7 allowing for movement of the pump rod independently of the windmill rod.

65 It might be further stated, however, that before connecting the pump handle to the pump rod 6, the pump rod 6 is moved until the bolt 8 rests at the lower end of the elongated opening or slot.

70 In the form of the invention as shown by Figure 4 of the drawings, the sleeve which is indicated by the reference character 17, is formed with an elongated opening 18, while the pump rod 19 is provided with an opening to receive the bolt 20, that connects the sleeve and pump rod. This structure is the reverse of that shown by Figures 1 and 2 of the drawings.

I claim:

75 A coupling for coupling a windmill rod and pump rod, said coupling comprising a sleeve, one wall of the sleeve extending an 80

appreciable distance beyond the end of the sleeve, securing plates adapted to be secured to a windmill rod, means for pivotally connecting the extension to one of the securing plates, one wall of the sleeve adjacent to the opposite end of the sleeve being cut away to permit the sleeve to be positioned over a pump rod, means for securing the sleeve to the pump rod, said means including a pin and elongated opening in the pump rod.

In testimony that I claim the foregoing as my own, I have hereto affixed my signature.
